FISHING REEL

Koji Endo, Tokyo, and Tsuneharu Fukazawa, Saitama,
Japan, assignors to True Temper Corporation, Cleve-
land, Ohio

Filed Nov. 2, 1970, Ser. No. 25,778

Term of patent 14 years

Int. Cl. D22—05

U.S. Cl. D22—25

Fig. 1

Fig. 2

Fig. 3

Fig. 4

Fig. 5

FIG. 1 is a side elevation of a fishing reel of our new design;

FIG. 2 is a plan view of the same;

FIG. 3 is an end view of the same;

FIG. 4 is a side elevation of the same from the side opposite FIG. 1; and

FIG. 5 is a front view of the same.

We claim:

The ornamental design for a fishing reel, as shown and described.
